COMBINATION SWITCH

Roy E. Clubb and Joseph P. Vennari,
St. Louis, Mo.

Application April 17, 1950, Serial No. 156,456

5 Claims. (Cl. 200—33)

1

The present invention relates generally to the switch art and more particularly to a novel combination time controlled and manually operable electric switch of a size to be contained within the standard switch and receptacle box.

In one form, the combination switch comprises a housing containing a pair of terminal posts and two electrical circuits, each of which includes a switch element, contained within the housing and connected in parallel between the two terminal posts. In one circuit the switch element therein is actuated by a manually operable lever which is moved to one position to open the circuit and another position to close it. In the other circuit, the switch element is automatically actuated by a lever which is pivotally mounted within the housing and movable between a first and second position, the lever opening the switch element when it is in the first position. The automatically operable lever is manually movable from the first position to the second position and when it is so moved, it compresses a spring which urges it toward the first position so as to actuate the switch element. Means are provided for controlling the rate of movement of this lever toward the first position, which, in the preferred form, is a watch type escapement mechanism. A friction clutch connects the last named means with the lever so that the latter can be manually moved between the two positions, and particularly from the first to second position, without adversely affecting the mechanism controlling the rate of movement of the lever toward the first position.

There are numerous time controlled switches in use at the present time which actuate a switch element after a predetermined period of time has elapsed, but most of these are very large and expensive, and are not particularly advantageous for use by the average home owner.

It is an object of the present invention, therefore, to provide a novel combination switch for controlling lighting circuits and the like, which is inexpensive and which contains both a time control actuator and a manually operable actuator.

Another object is to provide a combination switch of this type which is of a size to fit within the standard switch and receptacle box so that it can be used with existing equipment.

Another object is to provide a combination switch in which the accuracy of the time interval controlled by the position of the time control lever, is maintained within predetermined limits.

Other objects are to provide a combination switch which is compact in size, rugged in construction, and which is relatively inexpensive to manufacture.

Further objects and advantages of the present invention will be apparent from the following description, reference being had to the accompanying drawing wherein a preferred embodiment of the present invention is shown, in which:

2

Fig. 1 is a top plan view of a combination switch embodying the teachings of the present invention;

Fig. 2 is a front elevational view of the switch;

Fig. 3 is a side elevational view taken from the right of Fig. 2;

Fig. 4 is an enlarged vertical sectional view taken on the line 4—4 in Fig. 2, showing the time control lever in the inoperative or "off" position;

Fig. 5 is an enlarged vertical sectional view taken on the line 5—5 in Fig. 2, showing the manually operable lever in the inoperative or "off" position;

Fig. 6 is an enlarged horizontal sectional view taken on the line 6—6 in Fig. 3, a portion of the watch mechanism case being broken away to show the clutch housing;

Fig. 7 is a vertical transverse sectional view taken on the line 7—7 in Fig. 5, showing the cam member in the operative position whereby it opens the time control circuit of the switch;

Fig. 8 is a fragmentary view similar to Fig. 7, the lower half being omitted to conserve space, but showing the cam member in the inoperative position, whereby the time controlled circuit of the switch is closed;

Fig. 9 is a vertical transverse sectional view taken on the line 9—9 in Fig. 5, the cam member being shown in the operative position, as in Fig. 7;

Figs. 10 and 11 are horizontal sectional views taken on the lines 10—10 and 11—11, respectively, in Fig. 5;

Fig. 12 is a perspective view of the manually operable dog;

Fig. 13 is an enlarged elevational view of the clutch and clutch housing, shown removed from the watch mechanism case;

Fig. 14 is a horizontal sectional view taken on the line 14—14 in Fig. 13; and

Fig. 15 is a schematic wiring diagram of the switch.

Referring to the drawing more particularly by reference numerals, 20 indicates generally a combination switch constructed in accordance with the teachings of the present invention.

The switch 20 includes a main housing 22 which has a U-shaped wall 24 which forms the top, back and bottom portions of the housing (Fig. 4).

A somewhat semicircular shaped side wall 26 is formed integral with the U-shaped wall 24 at the left side as viewed in Figs. 2, 7 and 9.

Flange portions 28 (Fig. 4) extend upwardly and downwardly from the U-shaped wall 24 at the front of the housing 22 and contain openings 30 therein for mounting the device in a standard switch and receptacle box, as will appear.

Formed integral with the housing 22 at the junction of the flange portion 28 and the U-shaped wall 24 are a pair of bosses 32 which contain openings 34.

A somewhat semicircular shaped wall 36 is re-

movably fastened to the right side of the housing 22 by bolts 38 which are disposed in the openings 34.

A shoulder 40 (Figs. 7 and 9) is formed adjacent the bottom of the housing 22 at the junction of the left side wall 26 with the bottom portion of the U-shaped wall 24.

Disposed between the two side walls 26 and 36 is a central wall 42, the bottom end of which is disposed adjacent the shoulder 40 and the upper end thereof is maintained in spaced position by a first threaded terminal post 43 (Fig. 9) which extends through the left side wall 26. As shown in Fig. 5, the central wall 42 stops short of the rear portion of the curved wall 24 of the main housing 22 so as to define a chamber therewith.

Nuts 44 and 45 (Fig. 9) are disposed on the end of the terminal post 43 which extends outwardly beyond the left side wall 26, and the end of a conductor 46 is connected to the terminal post 43 between said nuts, the latter holding the end of the conductor 46 securely in position.

Both a time controlled circuit and a manually operable circuit are contained within the housing 22. The manually operable circuit will be described first.

As shown in Fig. 9, a short length of insulated wire 47 extends downwardly from the first terminal post 43 to a point opposite the shoulder 40. An opening 48 (Fig. 11) extends transversely through the left side wall 26 and the shoulder 40, and disposed therein is a short cylindrical conductor 50.

The lower end of the wire 47 is connected to the left end of the conductor 50, as by soldering.

Disposed on each side of the central wall 42 and extending around the bottom edge thereof, is a J-shaped sheet of electrically conducting material such as copper, and which has a short leg portion 52 and a long leg portion 54, the short leg portion 52 being disposed between the central wall 42 and the shoulder 40 so as to be in electrical contact with the right-hand end of the cylindrical conductor 50. The long leg portion 54 extends upwardly toward the center of the central wall 42 to a trunnion 56 (Fig. 5) which extends between the central wall 42 and the right side wall 36, the long leg portion 54 thereby forming an electrical connection between the cylindrical conductor 50 and the trunnion 56.

Pivotedly mounted on the trunnion 56 is a dog 58 made of electrically conducting material in the form shown in Fig. 12. The dog 58 contains a notch 60 at one end and a finger-like portion 62 at the other end.

A shaft 64 (Fig. 7) which is in the form of a bolt extends from the central wall 42 through an opening in the right side wall 36 to a position outside the housing 22, and a nut 66 is disposed on the exposed threaded end thereof.

Pivotedly mounted on the shaft 64 within the housing 22 is a manually operable control lever 68 (Fig. 5), the free end of which extends from the open end of the housing 22. The lever 68 is made from an electrically non-conducting material, such as Bakelite. A curved spring 70 (Fig. 5) is fastened on one side of the lever 68 by a rivet 72, the curved inner end of the spring being disposed in the notch 60 in the dog 58 whereby the latter is actuated by the lever 68. The curved end of the spring 70 is farthest from the control lever 68 when the latter is in either extreme position and closest to it when the lever 68 is at the center of its travel. Because of this, the lever 68 will remain in either of its selected extreme

positions until moved to the other position. In moving it from one position to the other the spring 70 will be forced against the side of the lever 68. After the lever 68 has passed the midpoint of its travel between the two extreme positions, the force of the spring 70 urging the curved end thereof away from the lever 68, causes the pivotal movement of the dog 58 to accelerate, so that a snap action is provided.

Stop members 74 and 76 (Fig. 5) are disposed between the central wall 42 and the right side wall 36 so as to limit the pivotal movement of the lever 68.

Adjacent the finger-like portion 62 of the dog 58 is a second threaded terminal post 78 (Figs. 5 and 7) which extends from the inner wall 42 through an opening in the right side wall 36 to a point outside the housing 22. A nut 80 is threadedly disposed on the exposed end of the terminal post 78 so as to maintain the end of a conductor 82 in contact therewith.

As shown in Fig. 5, the manually operable lever 68 is movable between two extreme positions which are determined by the stop members 74 and 76. In the position shown in full lines, the finger-like portion of the dog 58 is pivoted away from the second terminal post 78, and in the position shown in dotted lines it is in electrical contact with the terminal post 78. When in the latter position, a circuit is completed from the conductor 46, through the first terminal post 43, the insulated wire 47, the short cylindrical conductor 50, the short leg portion 52 and long leg portion 54 of the J-shaped sheet, the dog 58, and the second terminal post 78, to the conductor 82. This circuit is shown schematically in Fig. 15.

The time controlled circuit which is in parallel with the previously described manually operable circuit, will now be described.

Extending upwardly from the second terminal post 78 adjacent the central wall 42, is a resilient contact blade 84 of electrically conducting material. The upper end of the blade 84 is adjacent the inner end of the first terminal post 43 (Fig. 9) which extends through the central wall 42, and is urged against it by the resiliency of the blade itself. When the upper end of the blade 84 is in contact with the inner end of the first terminal post 43, an electrical circuit is made from the conductor 46, through the first terminal post 43, the blade 84, and the second terminal post 78 to the conductor 82.

As shown in Figs. 5 and 7, an elongated rectangular shaped notch 86 is contained in the central wall 42 adjacent the upper end of the blade 84. Pivotedly mounted within the notch 86 is a cam member 88.

A time control lever 90 is pivotally mounted within the housing 22, as will appear, and the free end thereof protrudes out of the housing 22 between the left side wall 26 and the central wall 42 so as to contact the enlarged end of the cam member 88 when it is in one extreme position. Thus, when the free end of the time control lever 90 is adjacent the enlarged end of the cam member 88 as shown in Figs. 7 and 9, the latter is forced against the upper end of the blade 84 so as to move it away from the inner end of the first terminal post 43, whereby the above described circuit is opened. However, when the lever 90 is manually moved downwardly away from the enlarged end of the cam member 88, the blade 84 returns to the position shown in Fig. 8 and against the inner end of the terminal post 43.

The lower end of the time control lever 90 is fastened to a shaft 92 (Fig. 6) which is rotatably mounted in an opening 94 contained in the left side wall 26.

As shown in Figs. 4 and 5, two bosses 96 are formed integral with the U-shaped wall 24 adjacent the rear portion of the main housing 22 and contain threaded openings 98.

An elongated supporting plate 100 extends between the two bosses 96 and is fastened thereto by screws 102 which are disposed in the openings 98.

Fastened to the supporting plate 100 adjacent the center thereof is a cup shaped housing 104 (Figs. 5 and 6) which contains a helically coiled spring 106, the outer end of the spring 106 being fastened to the housing wall as shown in Fig. 4. One end of the shaft 92 extends into the housing 104 and is fastened to the inner end of the coiled spring 106 (Fig. 4). Thus, when the time control lever 90 is moved from the position shown in solid lines in Fig. 4, to the position shown in dotted lines therein, the spring 106 is contracted so that there is a force tending to return the lever 90 to the position shown in solid lines.

Connected to the other end of the shaft 92 is a mechanism which controls the rate of movement of the lever 90 toward the position shown in solid lines, and which will now be described.

As shown in Figs. 6 and 14, a cup shaped clutch housing 108 is rotatably mounted on a reduced portion of the shaft 92 at the end opposite to the one fastened to the spring 106. The housing 108 contains a sprocket wheel portion 110 and an annular flange portion 112.

Fastened to the shaft 92 within the housing 108 is a transversely extending rod 114 (Fig. 13). A semicircular shaped clutch band 116, having inwardly extending end portions 117 and made of resilient material, is disposed on each side of the rod 114. The outer peripheral surfaces of the bands 116 bear against the inner surface of the flange portion 112, and the inwardly extending end portions 117 bear against the rod 114. This frictional engagement of the bands 116 with the inner surface of the flange 112 tends to cause the shaft 92 and the clutch housing 108 to rotate together, but permits relative movement between them when the force on the shaft exceeds a predetermined amount.

The sprocket wheel portion 110 of the clutch housing 108 is part of a watch escapement mechanism 118 which is contained in a case 120 fastened to the left side wall 26 external to the main housing 22.

The watch escapement mechanism 118 includes a standard balance wheel and hairspring (not shown) which are driven from the sprocket wheel portion 110 through a gear train (not shown). Thus, when there is a force exerted against the sprocket wheel portion 110 tending to rotate it in one direction, the latter will rotate and cause the balance wheel and hairspring to oscillate at a substantially constant predetermined speed regardless of slight variations in the force urging rotation of the sprocket wheel portion 110. In the present case the force urging rotation of the sprocket wheel portion 110 is the helically coiled spring 106, as will appear.

When the time control lever 90 is moved downwardly from the position shown in full lines in Fig. 4, the shaft 92 is rotated in the counterclockwise direction (Fig. 4). This causes the helically coiled spring 106 to be contracted and also causes

the rod 114 to rotate, and the clutch bands 116 to slip within the clutch housing 108. The clutch housing 108 does not rotate with the shaft 92 when it is turned in this direction because the sprocket wheel portion 110 can rotate in only one direction due to the construction of the watch escapement mechanism 118.

When the lever 90 is released, the spring 106 starts to unwind and urges the shaft 92 to rotate in the clockwise direction, tending to return the lever 90 to the position shown in full lines in Fig. 4. This rotation of the shaft 92 causes rotation of the rod 114 and the clutch bands 116. The clutch bands 116 bearing against the inner surface of the flange portion 112 drive the sprocket wheel portion 110, which in turn causes the balance wheel (not shown) to oscillate at a predetermined rate.

As the lever 90 approaches the position shown in full lines in Fig. 4, its free end contacts the enlarged end of the cam member 88, thereby causing it to pivot in the clockwise direction as viewed in Figs. 7 and 9, so as to force the free end of the blade 84 away from the end of the first terminal post 43 and thereby open the circuit between the first and second terminal posts 43 and 78.

A cover plate (not shown) for the switch and receptacle box (not shown) contains a scale graduated in units of time so that the lever 90 can be set to open the circuit after a predetermined time interval.

In use, the combination switch 20 is fastened within a standard type switch and receptacle box (not shown) by means of screws (not shown) which extend through the openings 30.

The switch 20 is particularly applicable for use in a garage or the like, where it is desirable to have the light remain energized for a predetermined length of time, as for example, for the time it takes the user to walk from the garage to the house.

Thus, let us assume that a person goes into the garage at night to find a tool, or for some similar reason. On entering the garage he would move the manual control lever 68 downwardly to the position shown in dotted lines in Fig. 5, thereby closing the circuit through the insulated wire 47, the cylindrical conductor 48, the J-shaped sheets 52-54, and the dog 58, as described above.

After locating the tool, he would then move the time control lever 90 downwardly to the marking on the scale on the cover plate which corresponds to the time it requires him to walk from the garage back to the house, and then move the lever 68 upwardly to the position shown in full lines in Fig. 5. The movement of the lever 68 causes the dog 58 to snap away from the terminal post 78, thereby opening the manually controlled portion of the circuit. However, when the lever 90 was moved downwardly it permitted the cam member 88 to pivot and cause the free end of the blade 84 to contact the end of the terminal post 43, thereby completing the time controlled portion of the circuit so that the light 50 remains energized.

After the lever 90 is released, the helically coiled spring 106 urges it upwardly toward the enlarged portion of the cam member 88 and the watch mechanism 118 permits it to return at a predetermined speed.

When the free end of the lever 90 strikes the enlarged portion of the cam member 88, the blade 84 is moved away from the terminal post 43, as described above, thereby opening the time con-

trolled portion of the circuit so as to de-energize the light. If the operator changes his mind as to the setting of the time interval, the lever 90 can be easily and quickly reset without adversely affecting the watch mechanism 118. The construction of the clutch as described previously is such that the clutch bands 116 can be manually rotated within the housing 108 in either direction without injuring the mechanism 118.

Thus, it is apparent that there has been provided a novel combination manual and time controlled switch which fulfills all of the objects and advantages sought therefor.

The time control lever 90 can be set at any predetermined time (within limits determined by the particular watch mechanism) and after the predetermined period of time has elapsed, the circuit will be automatically opened.

The accuracy of the time interval indicated by the position of the lever 90 can be of any degree desired, being dependent solely upon the type of watch mechanism used.

The combination switch is small and compact so that it will easily fit within the standard switch and receptacle box, whereby it can replace existing switch equipment without requiring any modification or replacement of the existing leads or receptacles.

The friction clutch permits the time control lever to be moved manually in either direction without adversely affecting the watch mechanism, yet it is positive in its action in controlling the rate of movement of the lever toward the switch-element-actuating position.

Furthermore, the switch contains a minimum number of parts and is relatively inexpensive to manufacture.

It is to be understood that the foregoing description and the accompanying drawing have been given only by way of illustration and example, and that changes and alterations in the present disclosure, which will be readily apparent to one skilled in the art, are contemplated as within the scope of the present invention, which is limited only by the claims which follow.

What is claimed is:

1. A device of the type described, comprising a housing; first and second terminal posts extending into the housing; a first electrical circuit between the two terminal posts including a first switch element mounted within the housing; a first lever member manually operable to actuate the first switch element; a second electrical circuit between the two terminal posts in parallel with the first circuit and including a second switch element mounted within the housing; means for actuating the second switch element including a second lever member movable between a first and second position; yieldable means urging said second lever member toward the first position; and means limiting the rate of movement of the second lever member toward the first position.

2. A device of the type described, comprising a housing; first and second terminal posts extending into the housing; a shaft mounted within the housing; an electrical connection between the first terminal post and the shaft; a dog pivotally mounted on the shaft and movable between a first position in contact with the second terminal post and a second position away from it; a first lever for actuating said dog; a resilient blade element mounted within the housing and having one end thereof urged against the inner end of the first terminal post; means for moving the blade ele-

ment away from the first terminal post including a second lever pivotally mounted within the housing and movable between a first and second position; yieldable means urging the second lever toward the first position; and means controlling the rate of movement of said second lever toward the first position.

3. A device of the type described, comprising a housing; a switch element mounted within the housing; means for actuating the switch element including a shaft pivotally mounted in the housing and a lever fastened thereto; yieldable means urging rotation of the shaft in one direction; means for limiting the rate of movement of the shaft in said one direction; and a friction clutch interconnecting the shaft and said last named means, said clutch including a cylindrical housing, a rod-like member disposed diametrically within the housing, and a resilient band disposed on each side of the rod-like member in contact therewith and bearing against the inner surface of the cylindrical housing.

4. A device of the type described, comprising a housing; a switch element mounted within the housing; means for actuating the switch element including a shaft pivotally mounted in the housing and a lever fastened thereto; yieldable means urging rotation of the shaft in one direction; means for limiting the rate of movement of the shaft in said one direction; and a friction clutch interconnecting the shaft with said last named means, said clutch including a cylindrical housing, a rod-like member disposed transversely within the housing and fastened to the shaft, and a pair of semicircular shaped resilient bands having the free ends thereof bent inwardly, the bands being positioned within the housing so that they bear against the inner peripheral surface thereof and the inwardly extending ends are disposed against the rod-like member.

5. A device of the type described, comprising a housing; a contact; a resilient blade element mounted within the housing and having one end thereof urged against said contact; a cam member mounted in the housing adjacent the blade and movable to a position to move the blade element away from said contact; a lever pivotally mounted in the housing and movable between a normal first unoperated position and a second operated position, the lever actuating the cam member so as to move the blade element away from said contact when it is in the first position; a spring urging the lever toward the first position, said spring being capable of tensioning through the operation of said lever; and means limiting the rate of movement of the lever toward the first position operating through said spring.
